United States Patent Office.

JOHN B. ROOT, OF NEW YORK, N. Y.

Letters Patent No. 96,037, dated October 19, 1869; antedated October 13, 1869.

IMPROVEMENT IN THE ART OF MAKING METALLIC TUBES.

The Schedule referred to in these Letters Patent and making part of the same.

To all whom it may concern:

Be it known that I, JOHN B. ROOT, of the city, county, and State of New York, have invented a new and useful Improvement in Tubing, of which the following is a full, clear, and exact description, reference being had to the accompanying drawing, forming part of this specification, and in which—

Figure 1 represents a top view of a skelp, as the same is constructed to form my improved tubing;

Figure 2, a transverse section of the same;

Figure 3, a longitudinal section of said tubing; and

Figure 4, an outside longitudinal view thereof.

Similar letters of reference indicate corresponding parts.

My invention consists in a spirally-lapped metal tube, formed with a lock, following the direction of the spiral, by constructing the skelp, of which the tube or tubing is made, with a tongue and groove, or locking-ridge and furrow on reverse sides of its opposite edges, so that on spirally wrapping the skelp around a mandrel, its edges not only lap one over the other, but also establish a lock by the fit of the tongues in the grooves of the skelp, after which the tubing may be welded, or the spiral joint closed by soldering, or otherwise.

Referring to the accompanying drawing—

A represents a metal skelp, of any desired length, width, and thickness, according to the size and strength of the tubing to be made. Said skelp is formed with longitudinal grooves or furrows, *a*, and tongues or ridges, *b*, on reverse sides of its opposite edges. This may be done in one operation, by rolling the heated skelp, and the same heat subsequently serve to effect the spiral twist of the skelp around a rotating mandrel, in doing which, the edges of the skelp, during such formation of the tubing, are not only made to lap one over the other, but, by the fit of the tongues *b* in the grooves *a*, to establish a lock in direction of the spiral run of the skelp, free from any objectionable protrusion externally or internally, without scarfing the edges of the skelp. This tongue and groove, or ridge and

furrow-lock serve to hold the spiral lap of the tubing in place during the after-process of welding, soldering, or sealing the spiral joint, and materially add to the strength of the finished tubing, especially in direction of its length, and, furthermore, contribute to the closeness or tightness of the tubing.

A strong and close-lapped tubing may thus be made at but little expenditure of fuel, and with facility and dispatch, and a uniform width of lap, automatically secured, by the tongues and grooves of the skelp aiding to direct or gauge the lap.

While it is desirable, for the purposes of strength and smoothness, or regularity of surface in such tubing, to form the skelp with tongues and grooves of equal size, or thereabouts, on both of its sides or faces, as represented and described, such construction may be modified by constructing the skelp with simply or mainly a groove or furrow along its one edge, on its one side or face, and a mere or prominent tongue or ridge along its other edge, on its opposite side or face, which construction will also produce a spirally-lapped tube or tubing, of the character specified, that is, with a lock following the direction of the spiral run of the skelp of which said tubing is made.

If necessary, the tubing may have any desired thickness or increased strength given to it by wrapping, preferably, in a reverse direction, another skelp outside of or around it, and so on for any number of layers in succession.

What is here claimed, and desired to be secured by Letters Patent, is—

The improved method, herein described, of making tubes by rolling the skelp with longitudinal ridges and furrows, on its alternate edge-faces, and lapping the same in a spiral direction to form a lock, in the manner specified.

JOHN B. ROOT.
